CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA

BAFFLE FOR PULL RODS

Application filed September 28, 1926. Serial No. 138,201.

My invention relates to circuit interrupters and particularly to operating mechanism therefor.

One object of my invention is to provide a connection between the actuating mechanism for a group of circuit interrupters and the operating mechanisms of the several circuit interrupters that shall prevent the access of gases generated within the several circuit interrupters to the actuating mechanism.

Another object of my invention is to provide an inter-connection between the several circuit interrupters of a polyphase circuit-interrupter bank and the actuating mechanism therefor that shall prevent the pressure waves generated in the several circuit interrupters from being transmitted to the other circuit interrupters and the actuating mechanism.

20 In the patent to Harris No. 1,031,789, issued July 9, 1912, is shown and described a combination of circuit interrupters and an actuating mechanism that are connected by suitable link mechanisms that extend through 25 pipe or tube sections between the several circuit interrupters, and between them and the actuating mechanism.

In constructions embodying the principles of the above mentioned Harris patent, the 30 operating links extend directly through the several circuit interrupters and are, accordingly, exposed to the gases and pressure waves generated within the several circuit-interrupter casings upon the operation of the interrupters. Under conditions of severe service, oil and gases have occasionally been 35 transmitted through the pipe or tube sections from one circuit interrupter to another and to the actuating mechanism.

40 I propose to avoid the foregoing conditions by providing separate compartments for the circuit-interrupter-operating mechanism and the connections to the actuating linkage. Adjacent compartments are separated by a wall 45 through which a shaft, or other suitable moving element extends for transmitting energy from the actuating linkage to the operating mechanism of the associated circuit interrupter, without permitting the transfer of gases 50 and/or oil from the circuit interrupter to the

pipe or tube sections, encasing the actuating linkage.

In the accompanying drawings,

Fig. 1 is a sectional view of a circuit interrupter embodying my invention, taken along the section line I—I of Fig. 2;

Fig. 2 is a view, partially in elevation and partially in section, of a circuit interrupter embodying my invention, taken along the section line II—II of Fig. 1;

Fig. 3 is an elevational view of a circuit interrupter embodying my invention; and

Fig. 4 is a view, partially in elevation and partially in section, of such circuit interrupter taken along the section line IV—IV of Fig. 1.

Figs. 2, 3 and 4 collectively, represent a bank of circuit interrupters and their common actuating mechanism for controlling a three-phase circuit.

Referring to Figs. 1 and 2, my invention comprises, in general, a circuit interrupter that includes a pull rod 2 for controlling the connection between a plurality of relatively movable contact members (not shown) an operating mechanism 3 for actuating the pull rod 2 and a shaft 4 that extends into a compartment 5 containing mechanism 6 for connecting the shaft 4 to a link mechanism 7 which, in turn, extends, through suitable pipe or tube section 8, to an actuating mechanism 9.

The mechanical details of the pull rod 2 and the operating mechanism 3 may be of any preferred type, although I prefer to employ the type shown and described in my Patent No. 1,652,508 issued Dec. 13, 1927.

The operating mechanism 3 is mounted partially within the circuit-interrupter casing 1 and partially in a compartment 11 formed in the casing cover 12. A wall 13 separates the compartments 5 and 11 and is of sufficient rigidity to withstand the pressures incidental to the operation of the associated circuit interrupter 1. The shaft 4 is suitably packed in the wall 13 so that no gas is transmitted longitudinally of the shaft between the two compartments.

Referring to Figs. 1 and 4, in each of the compartments 5, the shaft 4 is connected,

by an arm 15, to the linkage mechanism 7 and, in all but the last of the circuit interrupter units, the links 7 are connected to a pin 16 that is connected to the arms 15 in order that the several links 7 shall be kept in alinement during movement of the shafts 4 and the arms 5.

When it is desired to operate one or more of the circuit interrupters 1, the actuating mechanism 9 is energized to move the linkage mechanism longitudinally of the pipe or tube sections 8 in the proper direction to open or close the interrupter, as desired. The linear motion of the links 7 is transmitted, through the several arms 15 and shafts 4, to the operating mechanism, or mechanisms, of the circuit interrupter, or circuit interrupters 1 and the latter are opened or closed, as desired.

When each circuit interrupter 1 is opened, an appreciable amount of gas is generated, the oil contained therein is violently agitated, and a pressure wave is developed by the arc drawn within the circuit interrupter. Such pressure wave and the gases incident thereto are confined within the compartment 11 and are prevented, by the walls 13, from passing into the compartment 5.

Accordingly, the danger of gases and hot insulating oil traversing the several pipe or tube sections 8 to adjacent circuit interrupter units 1 and the actuating mechanism 9, is prevented. When the circuit interrupters 1 are closed, very little arcing occurs and, accordingly, my invention is designed primarily for protecting the operating mechanism 9 when the circuit interrupters 1 are opened.

It will thus be seen that I have devised a connection between a single actuating mechanism and one or more circuit interrupters that is characterized by the transmission of energy from the actuating mechanism to the several circuit interrupters without the danger of gases and insulating oil being transmitted between the several circuit interrupters and between the circuit interrupters and the actuating mechanism.

I accomplish the above mentioned result by providing separate compartments in each of the circuit interrupters for the operating mechanism and for the connection of the actuating mechanism thereto. The two compartments are separated by a barrier through which a movable member extends and with which it makes a tight joint.

While I have shown but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. In a circuit interrupter, a casing de-

fining a plurality of compartments, operating mechanism for the circuit interrupter disposed in one of the compartments, actuating means for the operating mechanism disposed in another compartment, a shaft connecting the said two mechanisms passing through the wall of the compartment forming a gas tight joint therewith. 70

2. In a circuit interrupter, a casing defining a plurality of compartments, operating mechanism for the circuit interrupter disposed in one of the compartments, actuating means for the operating mechanism disposed in another compartment, and a rotatable shaft extending between the compartments passing through the wall thereof forming a gas tight seal therewith. 75 80

3. In combination, a plurality of circuit interrupters each having an operating mechanism and contact members within a chamber, a shaft having a crank on each of its ends supported near its mid portion by the wall of each said chamber, means on the said walls forming a seal with the said shafts, a longitudinally extending link interconnecting the cranks on the outside of the chamber, an actuating mechanism for the link and a container member for enclosing the last said cranks, the link, and the actuating mechanism. 85 90 95

In testimony whereof, I have hereunto subscribed my name this 13th day of September, 1926.

CHRISTIAN AALBORG.
